UNITED STATES PATENT OFFICE

2,063,484

SHOE RASPING DEVICE

William C. Card, Jr., Winthrop, Mass., assignor
to Compo Shoe Machinery Corporation, New
York, N. Y., a corporation of Delaware

Application December 13, 1933, Serial No. 702,110

2 Claims. (Cl. 12—17)

This invention relates to a machine for use in the manufacture of footwear and, more particularly, to that type of footwear wherein cement is used adhesively to affix an outer sole to 5 a lasted shoe upper.

Generally, it is an object of the invention to provide a machine which will rapidly, uniformly and efficiently remove hardened excess cement, rough edges, etc., from insoles which will be 10 simple and economical of construction, and which will operate with freedom from wear and mechanical difficulties.

Specifically, an object of the invention is to provide a mechanism which will effect the removal, from the insole of a semi-finished shoe, of excess hardened cement which has gathered because of seepage or as a result of the pressure brought to bear upon the lasted upper and outer sole during the sole affixing operation.

Another object of the invention is to provide 20 a machine which will efficiently and readily prepare the upper surface of the insole of a shoe for reception of a sock lining by removing substantially all traces of hardened excess cement, etc., to produce a smooth and even upper surface on 25 the insole.

Other objects of the invention will in part be obvious and will in part appear hereinafter.

The invention accordingly comprises the features of construction, combination of elements, and arrangement of parts, which will be exemplified in the construction hereinafter set forth and the scope of the invention will be indicated in the 30 claims.

For a fuller understanding of the nature and objects of the invention reference should be had to the following detailed description taken in connection with the accompanying drawing showing one embodiment of the invention, in 35 which:

Fig. 1 is a side elevational view, of a machine constructed in accordance with the invention showing a portion being broken away in order more clearly to illustrate a detail of construction; and

Fig. 2 is an enlarged detail view with parts broken away showing the parts of that portion of the machine which extend into the forepart of a shoe.

A machine constructed in accordance with the principles of this invention may be used with particular advantage in the manufacture of shoes having cut-out insoles, the outer soles of which are flush with the surface of the insoles and are 50 adhesively secured to the lasted upper by py-

roxyl cement or the like. Such a method of shoe manufacture is disclosed for example in the Sbicca Patent No. 1,838,708 issued December 29, 1931. However, as will be readily understood by one skilled in the art, the use of the improved machine will be found to be advantageous wherever it is desired to smooth or remove irregularities from the upper surface of the insole of a finished or lasted shoe.

Referring more particularly to the drawing, 10 there is shown a rigidly supported driving motor 10 to one end of which is secured a housing support 11, which carries a rigid curved housing 12 which extends toward the operator and thence downwardly and away from the operator, so that 15 its end is conveniently positioned for operating upon a shoe. The curved housing 12 encases a flexible shaft 13, one end of which is coupled with the motor shaft 14, and the other end of which is coupled in driving relation with a button rasp 15 which rotates on a substantially vertical axis 20 and has its operating face disposed substantially horizontally.

The driving motor 10 is rigidly supported in any convenient manner so as to have the button 25 rasp 15 in proper position with respect to the operator. For example it may be secured upon a pedestal 16 by means of bolts 17, the pedestal in turn being secured to a bench or table 18 by lag screws 19 or the like.

To the motor shaft 14 a sleeve coupling 20 is connected by means of a dowel pin 21, or other suitable fastening means, the other end of the coupling being firmly connected to one end of the flexible shaft 13. The flexible shaft 13 then 35 extends through the curved housing 12 and its other end is operatively connected to the button rasp 15 as shown, for example, in Fig. 2.

In Fig. 2, it will be observed that the outer end of the flexible shaft 13 is firmly connected to a 40 keyed coupling 27 which is keyed into a non-flexible extensor shaft 28 carried in a thrust-bearing 32 which is held in the outer end of the curved housing 12 by means of set screws 33. The extensor shaft 28 is provided with an enlarged portion 29 integral therewith which is recessed and slotted to receive a reduced extension 30 and its associated key 31 of the keyed coupling 27 whereby the flexible shaft 13 transmits its rotary motion to the non-flexible extensor shaft 50 45 28. Attached to the thrust-bearing 32 by means of set screws 35 is an angular housing 34 which encloses the bevel gears or equivalent mechanisms by which the button rasp 15 may be driven with its axis disposed substantially vertically and 55

its operating face disposed substantially horizontally. In the embodiment shown a bevel gear 36 is secured to the extensor shaft 28 in any suitable manner, for example by means of a pin 38 and is in turn meshed with a second bevel gear 37 which is horizontally mounted in the lower end of said angular housing which forms a bearing therefor. Screwed into the horizontally mounted bevel gear 37 is the aforementioned button rasp 15 having its horizontal face provided with rasp teeth 39. The bevel gear 37 is held in position by an end plate 25 secured to the housing 34 by means of set screws 26. The end plate 25 is provided with a stepped opening 44 forming a vertical thrust-bearing with the shank 45 of the button rasp 15. When it is desired to unscrew the rasp from its operative position in order to sharpen or replace it, the operator merely grasps the rasp and turns a hand knob 40 secured at the other end of the motor shaft 14 on the motor 10. In order to take up any slack, which might occur in the flexible shaft on account of use, or from other causes, and thereby forestall chattering, or in order to effect a desired adjustment, the housing support 11 is split a substantial distance beyond two clamping members 22 which have openings 23 adapted to receive two machine bolts for holding the housing in its adjusted position. The keyed connection between the coupling 27 and the extensor shaft 28 is sufficiently tight to permit this operation but nevertheless permits separation of the parts when it is desired to dismantle the machine or replace the parts.

35 Preferably the shaft housing is underslung toward the rear of the standard and driving motor and spaced a sufficient distance therefrom conveniently to allow a comfortable manipulation of a shoe during the rasping operation so that the 40 operator can see the work as it progresses, as illustrated in dotted lines in Fig. 1.

In order further to aid the operator a small electric lamp 41 and reflector 42 is mounted by a simple universal clamp 43 to the shaft housing 45 12, thus allowing the operator to adjust the position of the lamp and to provide a constant source of illumination to the inside of the shoe. It is 50 convenient and desirable that the lamp and reflector be mounted in cooperative relation with respect to the curved housing in such manner that the projected light rays also make an acute angle with the reflecting surface operated on by the rasp so that the entire forepart of the insole is 55 illuminated and the reflected light issues in a manner convenient for observation by the operator as the shoe is manipulated against the rasp.

It will thus be seen that by means of the present invention there has been provided a device which will rapidly and efficiently accomplish the 60 objects set forth and since certain changes may be made in the above construction and different embodiments of the invention could be made without departing from the scope thereof, it is intended that all matter contained in the above 65 description or shown in the accompanying draw-

ing shall be interpreted as illustrative and not in a limiting sense.

Having described my invention, what I claim as new and desire to secure by Letters Patent, is:

5 1. A machine for the removal of excess hardened cement formed in a cement constructed shoe during the sole affixing operation in the marginal forepart area at the juncture where the upper surface of a randed insole aligns with the upper surface of a landed portion of a complementary outsole comprising, in combination, a driving means having a rigid support, a rearwardly curved shaft housing extending toward said support and in spaced relation thereto with the upper end of said housing associated with 10 said driving means, a rotatable flexible shaft mounted in said housing and connected with said driving means, a horizontally disposed rotary cement removing rasp having a downwardly suspended horizontally disposed rasping face rotated by said shaft and associated with the lower end of said housing and projecting therebelow whereby said rasp is spaced sufficiently distant from said support and said housing to permit easy application and removal of a shoe and to allow 15 said rasp horizontally to operate upon the forepart of an insole of a horizontally positioned shoe so that said forepart of said insole as well as said rasp are at all times presented to the observation of an operator to disclose the progress and 20 permit control of the cement removing operation.

2. A machine for the removal of excess hardened cement formed in a cement constructed shoe during the sole affixing operation in the 25 marginal forepart area at the juncture where the upper surface of a randed insole aligns with the upper surface of a landed portion of a complementary outsole comprising, in combination: a driving means having a rigid support; a curved shaft housing the upper end of which extends 30 horizontally away from said driving means and toward an operator, the midportion thereof extending substantially vertically downwardly, and the lower portion extending obliquely away from said operator; a flexible shaft within said housing; a split shaft tensioning support to permit 35 forward and rearward movement of said shaft housing thereby taking up any slack or easing any tension upon said shaft; a horizontally disposed rotary cement removing rasp having a 40 downwardly suspended horizontally disposed rasping face rotated by said shaft and associated with the lower end of said housing and projecting and therebelow so that said rasp is spaced 45 sufficiently distant from said support and said housing to permit easy application and removal of a shoe by said operator and to allow said rasp horizontally to operate upon the forepart of an insole of a horizontally positioned shoe whereby 50 said forepart of said insole as well as said rasp are at all times presented to the observation of an operator to disclose the progress and 55 permit control of the cement removing operation.
